SHOE STRETCHING DEVICE

Filed April 7, 1928

UNITED STATES PATENT OFFICE

GEORGE S. LOVE, OF SAN FRANCISCO, CALIFORNIA, ASSIGNOR OF ONE-HALF TO THOMAS MULLENDER, OF SAN FRANCISCO, CALIFORNIA

SHOE-STRETCHING DEVICE

Application filed April 7, 1928. Serial No. 268,121.

This invention relates to improvements in shoe-stretching devices, and has for its primary object the provision of means whereby footwear of boot and shoe character may be simply and uniformly stretched simultaneously in all directions, through the manipulation of a single actuating means, without in any manner affecting the symmetry of the article by causing undue distortion or enlargement in any one particular direction, as ordinarily results from the use of present appliances, in which two operations in different directions are required to obtain a longitudinal and a lateral stretching.

15 A further object of the invention is the provision in a shoe-stretching device of an actuating member so positioned as to assume a central place in the shoe-upper when positioned for use, thus affording ready access 20 to the actuating member after insertion, as well as facilitating this insertion.

An additional object is to provide a shoe-stretching device of the character designated constituting a sectional last formed of four 25 divisional parts, comprising the toe, ball, instep and ankle portions, these being divided longitudinally into matching sections adapted to part vertically and provided with means mortised within these parts, as thus formed, 30 to cause the lateral expansion of the two halves relative to each other, and also combining means for causing the longitudinal movement of the heel-piece constituting the third section of the last or form.

35 Supplementary to the foregoing is that of providing a shoe-stretching device that is of simple and relatively cheap construction, readily inserted in place within the shoe, of easy and simple manipulation, and of positive 40 action in diverse directions.

In the accompanying drawings, forming a part of this specification, and, in which, similar characters of reference refer to like parts, throughout;

45 Figure 1 is a longitudinal view of my shoe-stretching device, taken along the vertical parting line dividing the last into two matching sections, showing the expanding members in section, the actuating means therefor 50 in elevation, and the heel-piece also operable

therethrough, the section being indicated by the line 1-1 in Figure 2;

Figure 2 is a plan section, taken through the last on the line 2-2, of Figure 1, showing the main last expanding member in place between the matching halves of the form, and also the rear end or ankle expanding member and the heel actuating member of the form;

55 Figure 3 is a transverse section, taken through the toe portion of the last or form, showing the toe expanding member in place between the vertically split halves thereof, the section being indicated by the line 3-3 in Figures 1 and 2; and

Figure 4 is a face view of the heel section 60 of the form or stretcher.

Referring to the drawings with greater particularity, the device shown comprises a sectional shoe last, or form, 5, formed of substantially three major parts embodying the 70 longitudinally divided matching sections 6 and 7 forming the toe section 8, ankle section 9, and instep section 10, divided vertically, as indicated at 12, and forming, as a whole, a shoe-fitting last having an attached heel 75 section 13 adapted for longitudinal movement relative to the last sections 6 and 7.

The various sections constituting the last, when in assembled relation, provide a shoe-fitting last of a size adapted for ready insertion 80 into shoes of varying sizes, carrying as constituent elements means for the simultaneous expansion of the various shoe parts for the more comfortable accommodation of the feet of those wearers so unfortunate as to 85 have provided themselves with undersized shoes.

The means for causing the expansion of the toe sections, the instep sections, and ankle sections of the divided sections 6 and 7 of the 90 last, comprises an elongated wedge-shaped member 14 mortised into these sections by means of mortises 16 and 17 formed respectively in the divided sections 6 and 7 of the last, as is clearly shown in Figures 2 and 3, 95 the general contour of these mortised openings conforming to that of the wedge and communicating rearwardly with cored openings 18 and 19 extending longitudinally through the ankle sections of the last and, 100

in turn, communicating in the ankle section 9 with convergent faces 20 and 21 formed respectively in the ankle portions of the divided sections 6 and 7 of the last.

• A substantially wedge-shaped ankle expanding member 22 fits into the opening 23 formed by the convergent faces 20 and 21 and functions to cause the expansion of the ankle sections of the last and to adjust the heel section 13 longitudinally to simultaneously stretch the shoe lengthwise.

The wedge-shaped member 14 and the member 22 are provided with axially aligned threaded bores 24 and 25, of right and left thread respectively, for the reception of the right and left threaded ends 26 and 27 of a revoluble spindle 28 positioned longitudinally in the hollow interior portions 18 and 19 of the last sections.

20 The actuating means for causing the rotation of the spindle 28 consists of a fixed bevel gear 29 and a meshing bevel gear 30 pinned to a vertically disposed shaft 31 projecting above the upper portion of the last and bearing a fixed hand-wheel 32 at its upper end. The shaft 31 is supported in position by means of a bearing bracket 33 having a vertically disposed boss 34 and a horizontally disposed boss 35 in which the spindle 28 is 25 free to rotate, the bracket being supported in position by means of a transversely arranged pin 36 having threaded ends 37 and 38 formed at its outer ends for the reception of nuts 39 and 40 and washers 41 and 42. The pin 36 30 has its extremities extending into opposed bores 43 and 44 formed in the ankle sections of the matching members 6 and 7, respectively, the bores being provided with shoulders 45 and 46 at their inner ends providing 35 openings of a size approximately equalling that of the diameter of the pin 36. The extremities of the pin are provided with coil springs 47 and 48 arranged between the washers 41 and 42 and the shoulders 45 and 46, 40 so that the urge of the springs will tend to normally hold the matching sections 6 and 7 together, the pin also serving as a support to assist in holding the shaft 31 and wheel 32 in upright positions.

50 The heel-piece 13 consists of a rounded block having a thrust-plate 49 secured in place upon its inner face by means of screws 50 and provided with a centrally disposed slot 51 terminating in a rounded inner opening 52 adapted to receive the outer end 27 of the spindle 28, as clearly shown in Figures 1 and 4.

60 The wedge member 22 abuts against the plate 49 of the heel piece and as the heel piece is moved rearwardly by the spindle to expand the ankle section of the last it simultaneously moves the heel piece outwardly to cause the lengthwise stretching of the shoe.

65 The outer end 27 of the spindle extends through the slotted plate 49 of the heel piece

13 and projects into an opening 52 formed in the heel piece for its reception, this projecting end serving as a guide or carrier for the heel piece to assist in holding the heel piece in position while the device is being inserted into the shoe.

When the device is in place in a shoe and the wheel 32 is turned in a clockwise direction, the expanding wedges 14 and 22 will be forced outwardly in opposed directions, resulting in uniform transverse movement of the sections 6 and 7 of the last and simultaneously causing the rearward movement of the heel piece 13 to cause the lengthwise stretching of the shoe, all sections, including the toe, ball, instep, ankle and heel sections of the shoe being simultaneously and uniformly stretched by the one single operation.

Having thus described my invention, I claim, and desire to secure by Letters Patent:

1. In a device of the class described, a sectional last embodying longitudinally disposed matching sections comprising toe, ball, instep and ankle sections and a detachable heel section, opposed expanding members interposed between said sections and adapted to cause lateral expanding movement of said matching sections and the longitudinal movement of said heel section, and actuating means mounted between said matching sections and coacting with said expanding members to cause the lateral movement of said matching sections and the longitudinal movement of said heel section to uniformly expand all portions of a shoe in a single operation.

2. In a device of the class described, comprising a sectional last embodying longitudinally disposed matching sections forming the foot portion of a shoe stretcher, a heel section detachably associated with said matching sections, expanding means coacting with said matching sections and said heel section to cause the lateral expansion of the former and the longitudinal movement of the latter, and actuating means common to both said expanding members to cause their longitudinal movement in opposed directions simultaneously.

3. In a device of the class described, a sectional last embodying longitudinally disposed matching sections forming the foot portion of a shoe stretcher, a heel section associated with said matching sections, a threaded spindle longitudinally disposed between said sections and having right and left threaded ends, expanding members carried by said spindles and adapted to expand said matching sections latterly and to move said heel section outwardly therefrom, and means carried by said spindle to cause its rotary movement to expand said members.

4. In a device of the class described, a sectional last embodying longitudinally divided matching sections forming the foot portions of a shoe stretcher, a heel section at the heel

end of said matching sections, a longitudinally disposed right and left threaded spindle mounted between said matching sections, mortised sections formed in said matching sections, wedge-shaped expanding members disposed in said mortised sections and having threaded openings to receive opposite extremities of said threaded spindle, and means co-acting with said threaded spindle to cause its rotary movement and the consequent movement in opposed directions of said expanding members to force said matching sections latterly and said heel section outwardly in one single operation.

5 5. In a device of the class described, a sectional last embodying longitudinally disposed matching sections forming the foot portion of a shoe stretcher, a heel section associated with said matching sections, a right and left 10 threaded spindle longitudinally disposed between said sections, expanding members carried by said spindle and adapted to expand said matching sections latterly and to move said heel section outwardly therefrom, and 15 means carried by said spindle and centrally disposed in the shoe upper to cause its rotary movement to expand said members.

In testimony whereof I hereunto affix my signature.

30 GEORGE S. LOVE.
